UNITED STATES PATENT OFFICE

2,605,485

LAST PULLER

Ross W. Mallery, Lebanon, Ohio, assignor to The Charles Meis Shoe Manufacturing Company, Cincinnati, Ohio, a corporation of Ohio

4 Claims. (Cl. 12—15.1)

This invention relates to last pullers for removing shoes from shoe lasts and more particularly to an improvement therein that will more positively grip the counter portion of a shoe or the strap of a strap heel shoe and will minimize and reduce the incidence of damage to shoes while they are being removed from the lasts.

An object of this invention is to provide a last puller that will engage the shoe counter portion, or the heel strap, in the case of open counter shoes, at the sides as well as at the rear of the last.

A further object of this invention is to provide a last puller having a horn that engages the shoe at the rear of the last and fingers at the sides of the horn that yieldingly engage the sides of the counter portion or heel of the last, so that the horn and fingers yieldingly engage and follow the contour of the sides and rear of the heel of the last during the operation of pulling a last from a shoe.

The above and other objects and features of the invention will in part be apparent and will in part be obvious from the following detailed description, and the drawing, in which:

Figure 1 is a perspective view, partly broken away and in section, showing a last puller constructed in accordance with an embodiment of this invention;

Fig. 2 is an enlarged perspective view of the last engaging part of the last puller; and

Fig. 3 is a view in horizontal section through the last at an elevation slightly above the counter or strap engaging surfaces of the last puller horn and fingers.

In the following detailed description, and the drawing, like reference characters indicate like parts.

In Fig. 1, a machine for pulling lasts is shown which includes a pedestal 10 having a last pin holder 12 at the top thereof on which a last 13 is mounted. A shoe 14 is shown mounted in place on the last, and therefore the major portion of the last is concealed in Fig. 1.

The shoe is removed from the last by a pedal operated shoe lifting horn 16. The horn is supported at its lower end on a pin 17 carried by a rocker lever 18. The rocker lever is supported by a shaft 19 carried by the pedestal. A tension spring 21 is secured to the lever 18 and to the horn, the spring urging the horn against the rear of the counter portion of the last.

The shoe lifting horn is raised through its shoe lifting stroke by a pedal 22 and a rod 23 connecting the pedal and rocker lever, as shown. The

shoe lifting horn has a hook shaped upper end 26 turned towards the end of the heel of the last, and fingers or bifurcations 27 and 28 at the sides of the horn. The hook has a rearwardly concave recess 29 into which the rear of the last is received. These fingers are pivotally supported at the rear of the hook on pins 30 and 31 and are yieldingly urged towards each other by a spring 32. The fingers are designed to engage the shoe last immediately below the sides of the shoe counter portion or the strap of the shoe in the case of a strap heel shoe, and the hook engages the last immediately below the shoe counter portion or strap at the rear of the last. Thus the shoe counter portion or strap is engaged at three locations, on both sides and at the rear when the lifting horn moves upwardly through its shoe lifting stroke.

In order that the spacing between the fingers 27 and 28 at closed position may be adjusted, set screws 33 and 34 may be provided. The inner ends of these screws engage the sides of the hook 26 of the shoe lifter, so that by turning them in or out the normal spacing of the fingers may be adjusted to suit operating requirements.

When a shoe is to be lifted off the last, the lifting horn will be in the position shown in Fig. 1. When pedal 22 is depressed, the lifting horn is moved vertically. The lifting horn also turns on pivot pin 17 as the hook portion follows the contour of the rear of the counter of the last, and fingers 27 and 28 move towards or away from each other as they follow the contour at the sides of the last. In this lift stroke, the counter portion or strap of the shoe rests on the inner edges of fingers 27 and 28 and the inner edge of the concavity 29 in the horn. As there is thus provided a relatively large area of contact with the shoe, the shoe lifter will not in the usual case, slip off the shoe and damage the same. Damage resulting from slippage in the use of prior art horns is well known to those skilled in this art, and the construction of the present last puller reduces the likelihood of such damage because the fingers and horn engage the shoe counter portion or strap not only at the rear end thereof but also on the sides. The horn and fingers closely follow the contours of the last and firmly engage the counter portion of the shoe throughout the stroke of the last puller so that danger of damage to shoes is minimized.

The last pulling device illustrated in the drawing and described above is subject to structural

modification without departing from the spirit and scope of the appended claims.

Having described my invention, what I claim as new and desire to secure by Letters Patent is:

1. A bifurcated last puller, comprising a vertically reciprocable shoe engaging horn and yieldingly mounted fingers projecting laterally from the shoe engaging part of the horn, for engaging the sides of the counter part of the last, said horn being yieldingly urged in a direction to engage the end of the counter part of the last, whereby when a shoe is on the last, the sides and end of the counter portion of the shoe are supported on the horn and fingers, the horn and fingers following the contour of the heel of the last as the horn is moved through its shoe lifting stroke to remove the shoe from the last.

2. A bifurcated last puller in accordance with claim 1 characterized by the fact that a stop is provided to limit the movement of said fingers 20

toward each other and that said stop is adjustable.

3. A device for removing a shoe from a shoe last which comprises means for holding the last, a horn engageable with the edge of the rear end of the counter portion of the shoe, and reciprocable along the heel end of the last, a pair of fingers hinged to opposite sides of the horn, said fingers engaging edges of the sides of the counter portion of the shoe when the horn engages the edge of the rear end thereof, and resilient means drawing the fingers together, whereby the fingers engage and follow the sides of the last as the device is advanced along the last.

4. A device in accordance with claim 3 characterized by the fact that the resilient means is a tension spring connecting the fingers.
